(57) CLAIM

The ornamental design for a bra with support and positioning features, as shown and described.

DESCRIPTION

The present application claims priority to co-pending U.S. patent application Ser. No. 16/410,038, filed on May 13, 2019, the contents of which are expressly incorporated by reference herein for all purpose.

FIG. 1 is a front perspective view of a bra with support and positioning features with environment.

FIG. 2 is a front perspective view of a bra with support and positioning features.

FIG. 3 is a rear perspective view thereof.

FIG. 4 is a front elevation view thereof.

FIG. 5 is a rear elevation view thereof.

FIG. 6 is an interior elevation view thereof.

FIG. 7 is a top plan view thereof; and,

FIG. 8 is a bottom plan view thereof.

The features shown with dash broken lines in the drawings form no part of the claimed design. The partial human figure shown with dot-dash broken lines in FIG. 1 illustrate environment and form no part of the claimed design.

1 Claim, 8 Drawing Sheets
